Olive Barnes

ATTORNEY

UNITED STATES PATENT OFFICE.

WILLIAM WALKER, OF ABERDEEN, WASHINGTON.

OIL-BURNER.

1,400,108.

Specification of Letters Patent. Patented Dec. 13, 1921.

Application filed June 6, 1921. Serial No. 475,200.

To all whom it may concern:

Be it known that I, WILLIAM WALKER, a citizen of the United States, residing at Aberdeen, in the county of Grays Harbor 5 and State of Washington, have invented certain new and useful improvements in Oil-Burners, of which the following is a specification.

This invention relates to oil burners; and 10 its object is the provision of a burner of this character which is peculiarly adapted for domestic purposes and which will afford a relatively high efficiency with an economical consumption of fuel.

15 With these and other ends in view, the invention consists in the novel construction, arrangement and combination of parts hereinafter described and claimed.

In the accompanying drawings,—

20 Figure 1 is a side elevation of an oil burner embodying my invention. Fig. 2 is a plan view of the same with one of the burner heads partly broken away. Fig. 3 is a transverse section on broken line 3—3 25 of Fig. 1. Fig. 4 is a detail sectional view of one of the burner heads. Fig. 5 is a vertical detail section through 5—5 of Fig. 2, parts being omitted.

In said drawings, the reference numeral 30 10 designates a hollow base member which is desirably rectangular in transverse section containing a chamber 11. This chamber serves as a reservoir for a mixture of hydro-carbon gas and air which is received 35 from the end 12 of a pipe 13 of less diameter than the chamber 11 and extends from one end of the latter to about the midlength of the same.

The other end of the pipe 13 communicates through a return bend 14 with a receptacle 15 serving as a mixing chamber and located at one side of the base member 10 adjacent to the inlet end of the pipe 13. Air is admitted from below through an opening 45 16 into the mixing chamber 15.

Plates 17 and 18 are removably secured to the receptacle to afford air tight closures for clean-out holes which are advantageously provided in the top and in one side, respectively, of the receptacle.

Connected to the receptacle 15 and in opposed relations with the inlet end of the return bend 14 is the discharge element 20 of a substantially horizontal coil of pipes 19 55 which constitutes a gas generator with respect to fuel oil delivered into the receiving

element 21 of the coil from any suitable source of supply, not shown. The fuel oil is supplied into said coil under pressure and to obviate its passing too rapidly therethrough the pipe coil is advantageously provided interiorly with a porous retarding agent such, for example, as fibrous asbestos indicated by 22 in Fig. 3.

The generating of gas from the oil is accomplished by means of a supplementary burner which is disposed below said coil and, as shown, comprises a horizontally arranged vessel 23 having orifices 24 in its top for the discharge of fuel gas received from the reservoir 11 through a hollow bracket 25 provided at one side of the base member 10.

Generation of gas within said coil is started by burning oil-saturated material in troughs 26 provided in the top of the vessel 23. Adjacent to each of its ends the chamber 11 is provided with passages 27 extending upwardly through tubular neck elements 28 of the base member.

Said necks are desirably square in horizontal sections and terminate in inwardly sloping sides to afford inclined bearing surfaces 29 and upwardly converging outlets for the respective passages 27.

Surmounting each of said necks is a hollow burner 30 having the shape of a parallelepiped comprising separable collar and head members 31 and 32. The collar member 31 is in the nature of a rectangular plate provided with a central hub element 33 80 which extends upwardly into the head and having a central aperture corresponding in shape to the tapering extremity of the respective neck for seating upon the same. Said hub is also provided with air inlet holes 34 which incline inwardly toward the axis of the neck as shown in Fig. 4. The head member 32 is provided along the bottoms of its side and end walls with rabbets, such as 35 to receive the supporting collar member 31. 90

The side walls 36 of said head member are each provided with a series of horizontal slits 37 through which the combustible gas-and-air mixture is emitted to be consumed outside of the head.

Above the neck and hub in each head 30 is provided a cap piece 38 which is recessed to fit over the hub and afford in its underside concavities 39 to provide communicative 110 connections between the inlets 34 and the throat passage in the neck which will direct

air from said inlets into the passage 27 in a generally downward direction as indicated by feathered arrows in Fig. 4.

Provided centrally in said cap is a plurality of slits 40 disposed longitudinally of the device and parallel to the side walls 36 of the head.

The slits 40, moreover, are arranged between relatively thin and deep bars or blades 41 which cause the gases to issue from a neck into the associated head in a plurality of thin streams to insure the gases being thoroughly mixed before the escape of the same through the burner head slits.

In use, kerosene or other suitable fuel oil is supplied under pressure into the pipe coil 19 and is at the beginning of operations converted into gas by burning oil-saturated waste or other material in the troughs 26. The resultant gas is delivered through the outlet end of the coil pipe 20 through a volume of primary air admitted into the mixing chamber in receptacle 15 through the bottom opening 16 thereof. The gas in traveling through the central portion of such mixing chamber acts by induction to cause the primary air to be conveyed with the gas through the return bend 14 and pipe 13 into the reservoir 11.

In thus traveling the air and gas is delivered in a mixed state into said reservoir whence it is utilized as the gas generating agent in the supplementary burner member 23. The mixture furthermore passes upwardly through the throat outlets in the necks 28 and the slits 40 of the respective caps 38 into the chambers of the burner heads 32. Before passing through the caps, however, the mixtures of primary air and gas encounter traversing currents of what may be termed secondary air admitted through the inlets 34 (Fig. 4) into the space in each throat immediately below the respective cap, and such secondary air becomes, in turn, mixed with the aforesaid mixture while accompanying the latter through the caps 38 and the chambers of the burner heads.

The devices for supplying the secondary air in proximity to the burner heads and the means for insuring their intermingling are important features of the present invention and serve to produce a fuel which will be burned outside of such heads with an absence of smoke.

What I claim, is:—

1. In an oil burner, a base member containing a gas reservoir and provided adjacent to each of its ends with an upwardly directed neck outlet, an oil-gas generator operated by means of an auxiliary burner receiving fuel from said reservoir, a receptacle containing a mixing chamber into which said generator extends, said receptacle hav-

ing an opening in the bottom thereof for the admission of primary air into said chamber, a return bend communicatively connecting said chamber with the end of the reservoir, a pipe provided within the latter and extending from the outlet end of said bend to approximately the midlength of the reservoir, a burner provided for each of said necks, said burners being provided with inlets for the admission of secondary air, a slotted cap piece provided within the head for the respective necks, said caps serving to deflect the secondary air into the passages of the necks to unite with the mixture of primary air and gas passing through the respective neck passages.

2. An oil burner of the character described comprising a gas reservoir, a gas generator including a burner supplied with fuel from said reservoir, a mixing chamber into which said generator extends, said mixing chamber being connected with the reservoir, said reservoir being provided with neck elements serving as outlets for the reservoir, burner heads, collars seated upon said neck elements and supporting the respective heads, said neck elements being provided with air inlet openings, and caps for the respective collars, each of said caps being provided with a plurality of apertures disposed above the associated neck passage and also having recesses in its underside to afford communication between said air inlets and a neck passage and arranged to direct the air toward the center of the latter.

3. An oil burner of the character described comprising a gas reservoir, a gas generator including a burner supplied with fuel from said reservoir, a mixing chamber into which said generator extends, said mixing chamber being connected with the reservoir by means of a return bend and a pipe which extends into said reservoir, said reservoir being provided with neck elements serving as outlets for the reservoir, burner heads having slits in opposite sides thereof, collars seated upon said neck elements and supporting the respective heads, said neck elements being provided with air inlet openings, and caps seated upon the respective collars, each of said caps being provided with a plurality of apertures disposed above the associated neck passage and also having recesses in its under side to afford communication between said air inlets and a neck passage and arranged to direct the air toward the center of the latter.

Signed at Seattle, Washington, this 23rd day of May, 1921.

WILLIAM WALKER.
